UNITED STATES PATENT OFFICE.

MAXIMILLIAN H. SPIELMAN, OF NEW YORK, N. Y.

ELECTRIC CIGAR LIGHTER.

Application filed December 10, 1920. Serial No. 429,646.

To all whom it may concern:

Be it known that I, MAXIMILLIAN H. SPIELMAN, a citizen of the United States, residing in New York, in the county of New York and State of New York, have invented certain new and useful Improvements in Electric Cigar Lighters, of which the following is a specification.

This invention relates to improvements in electric cigar lighters, and has for its object to provide a device of this character which is simple in construction, economical to manufacture, and efficient in use.

The invention further has for its object to provide an electric cigar lighter, the parts of which may be easily and quickly assembled. A further object of the invention consists in providing a heating unit of simple and inexpensive construction which may be readily removed and replaced by another heating unit in case it breaks or wears out.

In the accompanying drawings forming part of this specification, wherein I have shown a preferred embodiment of my invention for the purpose of illustrating the principle thereof,

Figure 1 is a side view of an electric cigar lighter constructed in accordance with my invention;

Figure 2 is a plan view thereof;

Figure 3 is a sectional view taken on the line III—III of Figure 2;

Figure 4 is a sectional view taken on the line IV—IV of Figure 3, the contact member and push button being shown in plan;

Figure 5 is a bottom plan view of the heating unit, and

Figure 6 is a plan view of the device, the casing cap and the heating unit being removed.

Referring to the drawings, the device is shown as comprising a casing, preferably formed of metal, consisting of a body portion 1 and an annular cap 2 provided with co-acting threads whereby the parts are detachably connected to one another. Removably positioned within the body portion of the casing is a chambered block 3 formed of a suitable insulating material such as porcelain or the like. Positioned within the chamber of the block 3 is a contact 4 which is secured to the block by a bolt 5 or the like carried by the upper wall of the block and extending through an opening formed therein. The bolt 5 also serves to secure a resilient contact 6 within a recess 7 formed

in the upper surface of the block, and constitutes an electrical connection between the contact 4 and the contact 6. The free end of the resilient contact 6 is offset in an upward direction, with respect to the end thereof which is engaged by the bolt 5, to an extent such that it will project to the center and extend above the upper surface of the block 3, as shown in Figure 3. Mounted within the chamber of the block 3 is an arc-shaped spring contact 8 having an upwardly extending lug 9 at one end thereof engaging within a recess 10 formed in the upper wall of the block whereby the spring contact is held against bodily movement. The free end of the spring contact 8 is in register with and normally spaced from the contact 4, but is adapted to be moved into engagement with the contact by means of a push button 11 projecting through an opening 12 formed in the side wall of the body portion 1 of the casing, the side wall of the block 3 being cut away as indicated at 13 to receive the inner end of the push button which engages the free end of the spring contact 8. Adjacent its inner end the push button is provided with a flange 14 to limit the outward movement thereof. The upper portion of the block 3 is reduced slightly, as shown in Figure 3, and upon this reduced portion is mounted an annular flanged contact member 15.

Positioned within the casing above the block 3 is a heating unit comprising a disc 16 formed of a suitable insulating material adapted to withstand a high heat, such as lava or the like, and having a spiral groove 17 formed in its upper surface within which is received a coiled wire 18 formed of a non-corrosive material which offers a high resistance to the passage of an electric current therethrough. One end of the wire 18 passes downwardly through a hole 19 in the center of the disc 16 and is secured to a metal terminal member 20 in any suitable manner, as for example by means of solder. The other end of the wire 18 extends downwardly through a hole 21 adjacent the periphery of the disc 16 and is bent outwardly to pass through a notch 22 formed in the lower surface of the disc, whereby the outwardly-extending free end of the wire is held against lateral movement. The notch 22 is preferably of a depth slightly less than the diameter of the wire 18 to insure that the wire will engage with the annular contact 15.

when the parts are assembled as hereinafter described. In order to insure that the coiled wire 18 will be positively held within the groove 17 it is preferably anchored or tied 5 in position at a plurality of points throughout its length, as indicated at 23, Fig. 2. The anchoring means each comprises a piece of wire or the like 24 folded upon itself at the central portion thereof and extending down- 10 wardly through a hole 25 formed in the disc 16, the bent portion of the wire straddling the wire 18 and holding it firmly seated within the groove 17, as shown in Fig. 3. The anchoring wire 24 is locked in position 15 by having its free ends bent outwardly in opposite directions as indicated in Figures 3 and 5. The lower surface of the disc 16 is preferably provided with recesses 26 to receive the bent ends of the anchoring wires 20 24 in order to protect them and to insure that they will not engage either of the contacts carried by the block 3.

When the heating unit is in position above the block 3, the centrally positioned terminal 25 member 20, to which one end of the resistance wire 18 is secured, engages the free end of the resilient contact 6, and the other end of wire 18, which extends outwardly from the disc 16, engages the annular contact 15. 30 The heating unit is held in position by the annular cap 2, the inner portion of which is sloped to engage the periphery of the disc 16 and the outer edge of the upper surface thereof, as shown in Fig. 3. The cap 2 thus 35 serves to center the disc with respect to the block 3, and as the cap is screwed into position upon the body portion 1 of the casing, the heating unit is drawn downwardly, thus insuring that the terminals of the resistance 40 wire 18 will be pressed into engagement with the contacts 6 and 15. It is pointed out that there is no interlocking engagement between the heating unit and the block 3, which 45 would necessitate the heating unit being positioned in a certain definite relation with respect to the block, and that whatever the position of the heating unit with respect to the block may be, the central terminal member 20 will engage the resilient contact 6 and 50 the outer end of the wire 18 will engage the annular contact 15. The device is connected to a suitable source of current, not shown, by the conductors 27 which are led into the casing through an opening 28 formed in the 55 rear wall of the body portion 1. One of the conductors is connected to the spring contact 8, preferably adjacent the fixed end thereof, in any suitable manner as, for example, by means of a solder, and the other of the conductors passes through a hole 29 formed in 60 the upper portion of the block 3 and is secured to the annular contact 15 in any suitable manner. As the free end of the spring contact 8 is normally out of engagement 65 with the contact 4, no current can flow

through the device. When it is desired to utilize the device for lighting a cigar or the like, it is merely necessary to press upon the push button 11 to cause the free end of the spring contact 8 to engage the contact 4 70 whereupon current will flow from one of the conductors 27 through spring contact 8, contact 4, bolt 5, resilient contact 6, resistance wire 18, annular contact 15, to the other conductor 27. The resistance wire 18 will 75 thereupon become heated to a degree sufficient to permit a cigar or the like to be lighted therefrom in the usual manner. Should the heating unit become unfit for use, for any reason, it is merely necessary to unscrew the cap 2, remove the heating unit, put a new heating unit in position, and then screw the cap in position upon the body portion of the casing. As it is not necessary to unfasten the terminals of the damaged heating unit from contact members within the casing and to attach thereto the terminals of the new heating unit, the replacing of the damaged unit by a new unit may be accomplished in the minimum length of time, and furthermore the change of units may be effected by unskilled persons without danger of causing short circuits between the current conducting parts of the device.

It is also pointed out that all of the current conducting parts of the device are so arranged that they cannot come into contact with the metal casing, thus insuring that the device may be handled with perfect safety.

While I have illustrated and described my invention in connection with a preferred embodiment thereof, it will be understood that I do not intend to limit myself to the specific embodiment shown, but that I intend to cover my invention broadly in whatever form its principle may be employed.

Having thus described my invention, I claim:

1. An electric cigar lighter including a block of insulating material, a centrally located contact arranged on the outside of said block of insulating material, an annular contact member arranged on the outside of said block of insulating material, a disc of insulating material having a hole thru its center and a hole near its edge, a high resistance wire supported by said disc on one surface thereof, a centrally located contact on the other side of said disc to which one end of high resistance wire is attached, the other end of the high resistance wire being led thru the hole near the edge of the disc, and a casing adapted to hold the block and the disc in co-operative relation with their centrally located contacts in engagement with one another and with the free end of the high resistance wire in engagement with the annular contact member.

2. An electric cigar lighter including a chambered block of insulating material, a

- centrally located contact arranged on the outside of said block of insulating material, an annular contact member arranged on the outside of said block of insulating material, 5 a disc of insulating material having a hole thru its center and a hole near its edge, a high resistance wire supported by said disc on one surface thereof, a centrally located contact on the other side of said disc 10 to which one end of high resistance wire is attached, the other end of the high resistance wire being led thru the hole near the edge of the disc, a casing adapted to hold the block and the disc in co-operative 15 relation with their centrally located contacts in engagement with one another and with the free end of the high resistance wire in engagement with the annular contact member, normally open switch contacts 20 located within the chambered block and controlling the circuit thru the contacts carried by the latter, and means extending thru said chambered block and thru the casing for closing said switch and contacts. 25 3. A heating unit for an electric cigar lighter comprising a disc of insulating material having a hole thru its center and a hole near its edge, a high resistance wire supported by said disc on one surface thereof, 30 one end of said wire being led thru the hole near the edge of the disc, and a centrally located contact on the side of said disc opposite to the side of which the high resistance wire is supported, to which contact the other end of said high resistance wire is secured. 35 4. A heating unit for an electric cigar lighter comprising a disc of insulating material having a hole thru its center and a hole near its edge and having on one side 40 a groove the ends of which terminate at said holes, a high resistance wire supported in said groove with its ends led thru said holes, and a centrally located contact on the side of said disc opposite the grooved side 45 to which contact is secured the end of the wire which is led thru the center hole in said disc. 5. A heating unit for an electric cigar lighter including a supporting member having a spiral groove formed in its upper surface, said supporting member having perforations formed therein at the ends of said groove, and a resistance wire disposed within said groove and having its end portions 50 extending through said perforations. 6. A heating unit for an electric cigar lighter including a supporting member and a resistance wire disposed upon top surface thereof and having its end portions extending through said supporting member, a terminal member secured to one of said end portions and lying adjacent the center of the lower surface of said supporting member, the exposed portion of the other of said end portions being bent to lie in the plane of the edge of the lower surface of said supporting member. 60

In testimony whereof I have affixed my signature to this specification.

MAXIMILLIAN H. SPIELMAN.
